SHOE SEWING MACHINE

Otto R. Haas, North Beverly, Mass., assignor to
United Shoe Machinery Corporation, Flemington, N. J., a corporation of New Jersey

Application October 18, 1941, Serial No. 415,571

8 Claims. (Cl. 112—61)

The present invention relates to shoe outsole sewing machines and more particularly to improvements in mechanisms for actuating the presser foot of an outsole stitcher of the type disclosed in U. S. Letters Patent to French and Meyer No. 473,870 of April 26, 1892, and in present inventor's application for patent Serial No. 294,926, filed September 14, 1939.

For actuating the presser foot in the machine of the patent and application above identified, the presser foot is secured to a lever having a ratchet on one arm arranged to be engaged by a pawl for locking the presser foot against the work. For clamping the work before a stitch is inserted during each sewing cycle, a second relatively movable arm having a ratchet is yieldingly connected with the presser foot lever and arranged to be engaged by a clamping pawl which is moved bodily while engaging the clamping ratchet. Before each feeding movement of the work, the presser foot is unlocked and the clamping pressure relieved, both pawls being held disengaged from their respective ratchets during feed of the work to permit the presser foot to accommodate itself with the thickness of the work at the end of the feeding operation. For actuating the pawls towards and from engagement with their respective ratchets and for moving the clamping pawl bodily, there is provided a single cam actuated lever on which the clamping pawl is mounted, a fixed pivot on the machine frame for the locking pawl, and a fixed stud on the frame against which the clamping pawl is engaged during movement of the cam lever to release the clamping pawl from its ratchet, the parts being so located that during downward movement of the cam lever, the lever will actuate the locking pawl away from its ratchet at substantially the same time the clamping pawl is released from its ratchet. In certain instances, due to manufacturing inaccuracies or to requirements met with special types of work, the actuation of the pawls towards and from their ratchets to cause the work to be clamped with a suitable pressure and released for feed does not occur simultaneously or sufficient movement is not imparted to one or both the pawls to accomplish the purposes intended. Numerous expedients have been adopted during manufacture of the machine, such as filing or bending the parts in order to avoid these difficulties, but where some change is necessary after the machine has been assembled, most expedients have been found to have undesirable results, such as increasing weakness in the parts or insufficient range of adjust-

ments. Furthermore, the location of the pawls and the cam lever in the machine renders them inaccessible for making accurate adjustments according to the usual expedients after the machine has been assembled completely, due to lack of space and obstruction by other operating parts of the machine.

The object of the present invention is to improve the construction and simplify the manner of assembly and adjustment either when the machine is being manufactured or at any time thereafter when changes in adjustment or timing are desired. In accordance with this object, the principal feature relates to the use of a cam lever having adjustable means for changing the times in each sewing cycle in which a presser foot locking pawl and a presser foot clamping pawl are actuated relatively to each other to lock the presser foot and to cause the presser foot to clamp the work in a shoe sewing machine of the type referred to having a fixed pivot for the locking pawl and a fixed stud against which the clamping pawl is engaged to cause the pawls to be released from their respective ratchets at the proper times. This feature of the invention also includes provision of means for changing the limits of movement imparted to the clamping pawl by the cam lever without changing the adjustment of relative timing between the pawls. In one form of the invention, the cam lever has connected with it an arm on which the clamping pawl is adjustably mounted and a locking pawl releasing arm pivotally mounted concentrically to the pivotal mounting of the clamping pawl lever, the locking pawl releasing arm being adjustably secured to the clamping pawl arm. In the preferred form of the invention, the fulcrum of the cam lever is adjustable to change the positions of the clamping pawl and releasing pawl arm simultaneously. These and other features of the invention, together with the construction, arrangements and combinations of parts hereinafter described and claimed, and the advantages to be obtained thereby, will readily be understood by those skilled in the art from the following description, taken in connection with the accompanying drawings, in which Fig. 1 is a sectional view of a portion of an outsole shoe sewing machine embodying the invention, parts having been broken away and removed to illustrate more fully the construction; Fig. 2 is a view on an enlarged scale of a cam actuated lever, pawls and ratchets for the presser foot mechanism of the machine illustrated in Fig. 1; Fig. 3 is a plan view of the cam

actuated lever and clamping pawl supporting arm of Fig. 2; Fig. 4 is a side view of a cam actuated lever and pawl supporting arm in the preferred form of the present invention; and Fig. 5 is a sectional plan view of the cam lever and clamping pawl supporting arm of Fig. 4.

The illustrated machine is an outsole stitcher of the same general construction and mode of operation, except as hereinafter described, as that disclosed in the patent and application above referred to, and is provided with a curved hook needle, a curved awl 2, and other stitch forming devices more fully disclosed in the patent and application. To hold the work in position against the thrust of the awl during sewing operations of the machine, the machine is provided with a work support 4 and a presser foot 6 actuated by suitably shaped cams on a sewing shaft 3 in timed relation with the stitch forming devices to clamp and release the work.

As in the machine of the patent and application, there is fulcrumed on a stud 10 secured in the main frame, indicated at 12, at the rear of the machine, a cam actuated lever 14 having a roll 15 engaging a cam on the sewing shaft. Pivotally mounted at the forward end of the lever 14 is a presser foot clamping pawl 16, arranged to engage a ratchet 18 secured to the free end of a clamping arm 20 loosely supported on a shaft 22 in the forward portion of the machine frame. After engagement with the ratchet 18, the pawl moves bodily with the lever 14 to clamp the work. Also loose on the shaft 22 is mounted a presser foot lever 24, to the forward end of which the presser foot 6 is fixed and to the rearward end of which a locking ratchet 26 is secured.

Cooperating with the ratchet 26 is a locking pawl 28 mounted on a fixed pivot 30 and pressed yieldingly towards the ratchet 26 by a hairpin spring 32. When the cam lever in the machine of the patent and application, which lever corresponds to the lever 14 in the present drawings, is moved downwardly by its cam, a projecting portion of the lever engages an arm on the pawl 28 and causes the pawl 28 to be disengaged from the ratchet 26. At the same time, a stud as at 34, fixed in the frame 12, is engaged by a shoulder on the pawl 16, causing the pawl 16 to be disengaged from the ratchet 18. To hold the presser foot with a light yielding pressure against the surface of the work when the pawls are released, at which time the feed takes place, the rearward end of the presser foot lever 24 is pressed upwardly by a light spring 35 acting on a link 36 connected to the lever 24. As the lever 14 is moved upwardly, a spring-pressed plunger 37 engaging a second shoulder on the pawl 16, causes it to be re-engaged with the ratchet 18. At the same time, the lever 14 allows the locking pawl 28 to re-engage the ratchet 26.

After the clamping pawl 16 engages the ratchet 18, further upward movement of the lever 14 exerts a yielding force through a spring 38 coiled about a link 40 slidably in a lug on the clamping arm 20 and pivotally connected to the rearward end of the presser foot lever 24, causing a clamping pressure of the presser foot to be exerted against the work on the work support. The pressure thus exerted on the work by the presser foot is thereafter maintained throughout a substantial portion of each sewing cycle by the locking ratchet and pawl, and is released only after the presser foot actuating lever is moved again downwardly.

In the machine of the patent and application,

the cam lever corresponding to the lever 14 with its clamping pawl supporting arm and its locking pawl releasing projection, are formed integrally with no opportunity for relative adjustment. In order to insure proper operation of the machine after factory assembly, or to render the operation effective with certain types of work, particularly with unusually heavy work, it is necessary to make certain adjustments, either to overcome manufacturing inaccuracies or to obtain proper clamping and releasing action of the presser foot as the thickness of the work for which the machine originally was adjusted to operate is changed. To make these adjustments, the machine is either partially dismantled and the parts filed or an attempt is made to bend the parts or to make suitable adjustments otherwise without removing the parts from the machine. A common expedient for changing the adjustment of the presser foot actuating mechanism without removing the parts from the machine is by bending the stud 34 in the proper direction to cause the clamping pawl 16 to disengage its ratchet 18 earlier or later than the movement of the lever 14 with respect to actuation of the locking pawl 28. Bending the stud 34 necessitates further adjustments in the time of operation of the locking pawl, and these changes in turn require further changes in the range of movement imparted by the cam to the lever 14. Frequent bending of the stud 34 results in breakage so that in any case it is necessary to dismantle the machine eventually for replacement of the stud 34. To facilitate adjustments, a stud similar to that indicated at 42 on which the cam roll 15 is mounted is sometimes made with an eccentric portion, so that the position of the roll may be changed on the lever but with this eccentric portion, the stud is relatively inaccessible in the machine, it being reached for adjusting purposes only by dismantling the machine, at least partially.

In order to avoid difficulties in adjusting the presser foot actuating mechanism both during factory assembly and also during operation when different qualities and thicknesses of work are to be sewed, the lever 14 of the present machine has a separate clamping pawl supporting arm 44 pivotally mounted on a bolt 46 secured in the actuating lever 14. The arm has a rearward extension through which passes a clamp bolt 48 engaging a slot in the actuating lever 14 and is forked at its forward end to receive the clamping pawl 16 on a horizontal pivot 50. By loosening the clamp bolt 48, the position of the arm 44 may be changed with respect to the lever 14, thus causing contact of the clamping pawl 16 with the stud 34 to disengage the pawl sooner or later from the ratchet 18 in each sewing cycle. Early disengagement of the clamping pawl causes late engagement and relatively light clamping pressure to be exerted on the work. Later disengagement results in earlier engagement and relatively heavy pressure on the work.

To enable a corresponding adjustment to be made in the locking pawl so that it will be operated to release the work as soon as the clamping pawl is disengaged, the projection for releasing the locking pawl 28 is formed on a second arm 52. The locking pawl releasing arm 52 is also pivotally mounted on the bolt 46 and has a rearward extension into which is threaded a clamp bolt 54 passing through a slot formed in the rearward end of the clamping pawl supporting arm 44. When the clamp bolt 54 is loosened,

the distance between the forward end of the clamping pawl releasing arm 52 and the clamping pawl supporting arm 44 may be set suitably to correspond to the relative distance between the fixed stud 34 and the fixed pivot 30 on which the locking pawl is mounted. With the arm 44 so set and the bolt 54 tightened, the pawls are actuated simultaneously towards and from their ratchets. If any adjustment is desired thereafter to enable the machine to operate successfully on heavier or lighter work or to cause the presser foot to exert a greater or less clamping force on the work, the clamp bolt 48 for the clamping pawl releasing arm 44 may be loosened to admit change in the position of the arm on the lever 14. With changes in position of the arm 44, no change occurs between the locking pawl releasing arm and the arm 44 which is clamped thereto, so that changes for variations in work thicknesses may be made independently of changes in relative times at which the locking and clamping pawls are released from their respective ratchets.

In a preferred form of the invention, eccentric adjusting devices for the clamping and locking pawls are provided, as illustrated in Figs. 4 and 5. The cam lever of this form of the invention is indicated at 56, fulcrumed on the stud 10 and arranged at its forward end to support the clamping pawl 16 instead of employing a separate arm, and the spring-pressed plunger 37 is mounted in the lever as in the patent and application. To provide means for adjusting the relative times of operation for the clamping pawl 16 and the locking pawl 28, a slot-ended arm 58 is rotatably supported by the lever 56 at its slotted end on a bolt 60 and is formed at its other end with a lateral locking pawl releasing projection 62 underlying the forward end of the cam lever 56. To hold the arm 58 in adjusted position, that end of the arm near the projection 62 is perforated to receive an eccentric sleeve 64 having a hexagonal collar. To support the sleeve, a bolt 66 is threaded into an opening in the lever 56, the bolts 60 and 66, when tightened, securing the arm 58 rigidly with the lever 56.

To regulate the limits of movement imparted by the cam lever to the clamping and locking pawls, the stud 10 is surrounded by an eccentric flanged sleeve 68 clamped within the split hub of the cam lever 56 by a draw bolt 70. Suitable spanner holes 72 are provided in the flange of the sleeve to enable the sleeve to be rotated easily. The eccentric adjusting devices enable the operator to regulate the presser foot operating mechanism more satisfactorily in certain respects than in the previously described embodiment of the invention, particularly where adjustments are made with work in the machine or with the springs for actuating the presser foot and locking pawls under tension as in ordinary operation of the machine. In other respects, the eccentric adjusting devices have the same advantages for regulating the actuation of the presser foot, as in the previously described embodiment. In either embodiment, the adjusting devices are easily accessible and readily operable so that a more accurate adjustment and resulting satisfactory operation than heretofore considered possible can be obtained from the machine with all types of work.

Having thus described the invention, what is claimed is:

1. A shoe sewing machine having, in combination, stitch forming devices, a work support, a

presser foot and mechanism for actuating the presser foot to clamp and release the work comprising a lever having a locking ratchet, a locking pawl for engaging the ratchet, a clamping arm having a ratchet connected to the presser foot, a clamping pawl for engaging the ratchet upon the clamping arm, a fixed pivot for the locking pawl, a fixed stud against which the clamping pawl is engaged to release said clamping pawl from its ratchet, a cam lever for causing both pawls to be actuated towards and from their respective ratchets and for moving the clamping pawl bodily to force the presser foot against the work, and adjustable means connected to said lever for changing the times in each sewing cycle at which the pawls are actuated relatively to each other.

2. A shoe sewing machine having, in combination, stitch forming devices, a work support, a presser foot and mechanism for actuating the presser foot to clamp and release the work comprising a lever having a locking ratchet, a locking pawl for engaging the ratchet, a clamping arm having a ratchet connected to the presser foot, a clamping pawl for engaging the ratchet upon the clamping arm, a fixed pivot for the locking pawl, a fixed stud against which the clamping pawl is engaged to release said clamping pawl from its ratchet, a cam lever for causing both pawls to be actuated towards and from their respective ratchets and for moving the clamping pawl bodily to force the presser foot against the work, and adjustable means connected to said lever for changing the times in each sewing cycle at which the pawls are actuated relatively to each other and for changing the limits of movement imparted to the clamping pawl by the cam lever without changing the adjustment of relative timing between the pawls.

3. A shoe sewing machine having, in combination, stitch forming devices, a work support, a presser foot and mechanism for actuating the presser foot to clamp and release the work comprising a lever having a locking ratchet, a locking pawl for engaging the ratchet, a clamping arm having a ratchet connected to the presser foot, a clamping pawl for engaging the ratchet upon the clamping arm, a fixed pivot for the locking pawl, a fixed stud against which the clamping pawl is engaged to release said clamping pawl from its ratchet, a cam lever for causing both pawls to be actuated towards and from their respective ratchets and for moving the clamping pawl bodily to force the presser foot against the work, and an arm on which the clamping pawl is mounted adjustably connected to the cam lever to change the time in each sewing cycle at which the pawls are actuated relatively to each other.

4. A shoe sewing machine having, in combination, stitch forming devices, a work support, a presser foot and mechanism for actuating the presser foot to clamp and release the work comprising a lever having a locking ratchet, a locking pawl for engaging the ratchet, a clamping arm having a ratchet connected to the presser foot, a clamping pawl for engaging the ratchet upon the clamping arm, a fixed pivot for the locking pawl, a fixed stud against which the clamping pawl is engaged to release said clamping pawl from its ratchet, a cam lever for causing both pawls to be actuated towards and from their respective ratchets and for moving the clamping pawl bodily to force the presser foot against the work, an arm on which the clamp-

ing pawl is mounted adjustably connected to the cam lever to change the time in each sewing cycle at which the pawls are actuated relatively to each other, and a locking pawl releasing arm adjustably secured to the arm on which the clamping pawl is mounted to enable the limits of movement imparted to the clamping pawl by the clamping lever to be changed without causing the adjustment of relative timing between the pawls to be changed.

5. A shoe sewing machine having, in combination, stitch forming devices, a work support, a presser foot and mechanism for actuating the presser foot to clamp and release the work comprising a lever having a locking ratchet, a locking pawl for engaging the ratchet, a clamping arm having a ratchet connected to the presser foot, a clamping pawl for engaging the ratchet upon the clamping arm, a fixed pivot for the locking pawl, a fixed stud against which the clamping pawl is engaged to release said clamping pawl from its ratchet, a cam lever for causing both pawls to be actuated towards and from their respective ratchets and for moving the clamping pawl bodily to force the presser foot against the work, an arm on which the clamping pawl is mounted adjustably connected to the cam lever to change the time in each sewing cycle at which the pawls are actuated, a locking pawl releasing arm pivotally mounted concentrically to the pivotal mounting of the clamping pawl arm, and means for adjustably securing the locking pawl releasing arm to the clamping pawl arm.

6. A shoe sewing machine having, in combination, stitch forming devices, a work support, a presser foot and mechanism for actuating the presser foot to clamp and release the work comprising a lever having a locking ratchet, a locking pawl for engaging the ratchet, a clamping arm having a ratchet connected to the presser foot, a clamping pawl for engaging the ratchet upon the clamping arm, a fixed pivot for the locking pawl, a fixed stud against which the clamping pawl is engaged to release said clamping pawl from its ratchet, a cam lever for causing both pawls to be actuated towards and from their respective ratchets and for moving the clamping pawl bodily to force the presser foot against the work, and adjustable means including an eccentric operatively connecting the lever and one of the pawls to enable the times in each sewing cycle at which the pawls are actuated to be changed relatively to each other.

7. A shoe sewing machine having, in combination, stitch forming devices, a work support, a presser foot and mechanism for actuating the presser foot to clamp and release the work comprising a lever having a locking ratchet, a locking pawl for engaging the ratchet, a clamping arm having a ratchet connected to the presser foot, a clamping pawl for engaging the ratchet upon the clamping arm, a fixed pivot for the locking pawl, a fixed stud against which the clamping pawl is engaged to release said clamping pawl from its ratchet, a cam lever for causing both pawls to be actuated towards and from their respective ratchets and for moving the clamping pawl bodily to force the presser foot against the work, and adjustable means including an arm arranged to cause the locking pawl to be disengaged from its ratchet and eccentric means operatively connecting the locking pawl releasing arm to the cam lever to enable the times in each sewing cycle at which the pawls are actuated relatively to each other to be changed.

8. A shoe sewing machine having, in combination, stitch forming devices, a work support, a presser foot and mechanism for actuating the presser foot to clamp and release the work comprising a lever having a locking ratchet, a locking pawl for engaging the ratchet, a clamping arm having a ratchet connected to the presser foot, a clamping pawl for engaging the ratchet upon the clamping arm, a fixed pivot for the locking pawl, a fixed stud against which the clamping pawl is engaged to release said clamping pawl from its ratchet, a cam lever for causing both pawls to be actuated towards and from their respective ratchets and for moving the clamping pawl bodily to force the presser foot against the work, adjustable means including an arm arranged to cause the locking pawl to be disengaged from its ratchet and eccentric means operatively connecting the locking pawl releasing arm to the cam lever to enable the times in each sewing cycle at which the pawls are actuated relatively to each other to be changed, a stud on which the cam lever is fulcrumed, and an eccentric sleeve on the stud rotatable to change the limits of movement imparted to the clamping pawl without changing the adjustment of relative timing between the pawls.
